UNITED STATES PATENT OFFICE.

ANDREW MAGNUS PETERSON, OF NEW ATHENS, OHIO.

CHIMNEY-CAP.

1,340,459.

Specification of Letters Patent. Patented May 18, 1920.

Application filed April 28, 1919. Serial No. 293,126.

To all whom it may concern:

Be it known that I, ANDREW MAGNUS PETERSON, a citizen of the United States of America, and resident of New Athens, county of Harrison, and State of Ohio, have invented certain new and useful Improvements in Chimney-Caps, of which the following is a specification.

This invention relates broadly to chimney caps, and it has for its primary object to provide a cap structure for chimneys, composed of tiles or blocks and embodying means whereby said tiles or blocks are permanently secured against the common 10 tendency to separate and become dislodged through long exposure to the elements.

A further object is to provide a chimney cap composed of interfitting blocks bound together in such manner that their relative 20 arrangement is permanently maintained irrespective of the extent of expansion and contraction to which they are subjected through wide ranges and rapid changes of temperature.

With these and other objects in view, the invention resides in the features of construction, arrangement of parts and combinations of elements which will hereinafter be fully described, reference being had to the 30 accompanying drawing, in which—

Figure 1 is a top plan view of the invention with portions of the concrete layer broken away; and—

Figs. 2 and 3 are sections of the same 35 taken substantially on the lines 2—2 and 3—3, respectively.

In said drawings like designating characters distinguish like parts throughout the several views.

The chimney cap comprises in its construction a plurality of tiles or blocks, of 40 molded clay or other suitable material, mounted upon the upper course of bricks 1 of the chimney. Said blocks are of two 45 types, lineal blocks 2 and corner blocks 3. Each lineal block is of approximately L-shape in cross section with the horizontal member 2^a thereof directed inward and constituting a flat ledge which extends through- 50 out the length of the block, while the upright wall member 2^b thereof rises to a considerable height above ledge 2^a and may have either a plain or ornamentally shaped upper edge, the blocks shown in the drawings being represented as having said edge 55 dentated or serrated.

The corner blocks 3 correspond in shape to the lineal blocks 2, except that each has at its outer end a wall member 3^c lying at a right angle to the wall member 3^b thereof, as 60 shown.

Formed in the ledge portion 3^a of each corner block adjacent to the angle between the wall members 3^b and 3^c is a socket 4, and extending inward longitudinally from said 65 socket throughout the length of said ledge is a groove or channel 5. Also extending at a right angle to said channel 5 from said socket to the inner lateral edge of said ledge is a groove or channel 6. 70

Each of the lineal blocks 2 has extending from end to end of the ledge 2^a thereof a groove or channel 7. The channels 7 of adjacent blocks 2 are disposed in alinement, and the channels of such of said blocks as 75 abut against a corner block 3 register either with a channel 5 or a channel 6 of the latter, according as such block 2 alines with or is disposed at a right angle to the corner block. 80

A metal tie-rod 8 having downturned ends 8^a is disposed within the alined channels at each of the opposite sides of the chimney cap with its said downturned ends 8^a received within the socket 4 of the corner 85 blocks 3 located on said side. In like manner tie the rods 9 extend across the ends of the cap, lying in the alined channels of said end, and have their downturned ends 9^a received in the sockets of the corner blocks 90 located on said end. Said rods 8 and 9, which are designed to secure the various blocks 2 and 3 in their proper relative positions, effectually preventing displacement or dislodgment, are adapted to permit unob- 95 structed expansion and contraction of the cap structure without in any way impairing their efficiency as securing elements. To this end, the dimensions of the sockets 4 are made sufficiently great to permit both of 100 maximum expansion and maximum contraction of the blocks without at any time placing undue strain upon said rods; that is, said sockets are made of such dimensions that complete freedom of movement of the 105 blocks is permitted within the range of expansion and contraction to which they are subjected under the influence of opposite extremes of temperature.

The body portions of the tie-rods received in the channels are embedded in a layer 10 of concrete which is preferably

disposed on the ledges 2^a and 3^a of the blocks, as shown; and, to avoid interference with free movement of the downturned ends of said rods in the sockets 4, the latter are 5 filled with sand 11 after the introduction of said rods and before the application of the cement layer 10.

When the chimney embodies a plurality of flues, as depicted in the drawings, a flat block 10 or blocks 12 having a thickness corresponding to that of the ledges of the various blocks 2 and 3 is mounted on the division 13 which separates the flues. Said block 12 has therein a longitudinally extending channel 14 15 adapted for the reception of a tie-rod 15. When such transverse tie-rod is employed, short registering grooves 16 are provided in the lineal blocks 2 against which the block or blocks 12 abut, such short grooves leading 20 to sockets 17 in which the downturned ends of the rod 15 are received.

From the foregoing it will be understood that I provide a chimney cap which is not only extremely simple in construction, but 25 which possesses superior durability.

What is claimed is—

1. A chimney cap comprising lineal blocks and corner blocks, each formed with an inwardly projecting ledge having a longitudinal channel in its upper face, each corner 30 block also having a vertically disposed socket therein with which the longitudinal channel thereof communicates and having a laterally extending channel leading from 35 said socket, and tie-rods disposed in said channels for securing said blocks against displacement, said rods having angular end portions received in the sockets of opposite corner blocks for interlocking the latter and 40 the interposed lineal blocks in place.

2. A chimney cap comprising lineal blocks and corner blocks, each formed with an inwardly projecting ledge having a longitudinal channel in its upper face, each corner 45 block also having a vertical socket therein with which the longitudinal channel thereof communicates and having a laterally extending channel leading from said socket, said

channels and said sockets forming the four sides of a rectangle, and a tie-rod disposed in 50 the channels of each of said sides and having downturned ends received in the sockets of opposite corner blocks, said sockets having relatively large dimensions to permit of a limited range of movement of said blocks 55 with respect to said rods.

3. A chimney cap comprising lineal blocks and corner blocks, each formed with an inwardly projecting ledge having a longitudinal channel in its upper face, each corner 60 block also having a socket therein with which the longitudinal channel thereof communicates and having a laterally extending channel leading from said socket, said channels and said sockets forming the four sides 65 of a rectangle, a tie-rod disposed in each of said sides and having downturned ends received in the sockets thereof, said sockets having relatively large dimensions to permit of a limited range of movement of said 70 blocks with respect to said rods, a sand filling for said sockets and a protective covering for said rods mounted on the ledges of said blocks.

4. A chimney cap comprising lineal blocks 75 and corner blocks, each formed with an inwardly projecting ledge having a longitudinal channel in its upper face, each corner block also having a vertical socket therein 80 with which the longitudinal channel thereof communicates and having a laterally extending channel leading from said socket, tie-rods disposed horizontally in said channels for securing said blocks against displacement, said rods having angular end 85 portions received in the sockets of opposite corner blocks whereby the latter and the interposed lineal blocks are secured in place, and a layer of concrete mounted on said ledges in covering relation to said rods. 90

In testimony whereof I affix my signature in presence of two subscribing witnesses.

ANDREW MAGNUS PETERSON.
